CLAIM

The ornamental design for a mount for gun scope, as shown and described.

DESCRIPTION

FIG. 1 is a left side elevational view of a mount for gun scope shown in its environment;

FIG. 2 is a left side elevational view thereof;

FIG. 3 is a top plan view thereof;

FIG. 4 is a bottom plan view thereof;

FIG. 5 is a right side elevational view thereof;

FIG. 6 is front elevational view thereof;

FIG. 7 is a rear elevational view thereof;

FIG. 8 is a left side elevational view of a mount for gun scope showing a second embodiment of my new design;

FIG. 9 is a top plan view thereof;

FIG. 10 is a bottom plan view thereof;

FIG. 11 is a right side elevational view thereof;

FIG. 12 is a front elevational view thereof; and,

FIG. 13 is a rear elevational view thereof.

The broken lines shown of the gun and gun scope in FIG. 1 are for illustrative purposes only and form no part of the claimed design.
